Primary Examiner — Susan Moon Lee(74) *Attorney, Agent, or Firm* — Brinks Hofer Gilson & Lione(57) **CLAIM**

We claim the ornamental design for a hand-held scanner, as shown and described.

DESCRIPTION

FIG. 1 is a perspective view of a hand-held scanner;

FIG. 2 is a top view, thereof;

FIG. 3 is a bottom view, thereof;

FIG. 4 is a left side view, thereof;

FIG. 5 is a right side view, thereof;

FIG. 6 is a rear view thereof; and,

FIG. 7 is a front view thereof.

Broken lines and portions contained within broken lines are not claimed.
